Delbert L. Byerly, Compton, Calif.

Application January 30, 1948, Serial No. 144,179

Term of patent 3½ years

(Cl. D71—1)

To all whom it may concern:

Be it known that I, Delbert L. Byerly, a citizen of the United States, residing at Compton, in the county of Los Angeles and State of California, have invented a new, original, and ornamental Design for a Buoyant Cruise Board, of which the following is a specification, reference being had to the accompanying drawing, forming part thereof.

Figure 1 is a view in side elevation of a buoyant cruise board embodying my new design;

Figure 2 is a view in bottom plan;

Figure 3 is a view in top plan;

Figure 4 is a sectional view taken substantially on the line 4—4 of Figure 3;

Figure 5 is a sectional view taken substantially on the line 5—5 of Figure 3;

Figure 6 is a sectional view taken substantially on the line 6—6 of Figure 3.

I claim:

The ornamental design for a buoyant cruise board, substantially as shown.

DELBERT L. BYERLY.
